UNITED STATES PATENT OFFICE.

GEORGE E. SPOFFORD, OF Langley, SOUTH CAROLINA, ASSIGNOR TO DRAPER CORPORATION, OF HOPEDALE, MASSACHUSETTS, A CORPORATION OF MAINE.

CROSS-WEAVING LOOM.

Application filed January 5, 1922. Serial No. 527,229.

To all whom it may concern:

Be it known that I, GEORGE E. SPOFFORD, a citizen of the United States, residing at Langley, in the county of Aiken and State 5 of South Carolina, have invented an Improvement in Cross-Weaving Looms, of which the following description, in connection with the accompanying drawings, is a specification, like characters on the drawings representing like parts.

This invention relates to cross weaving looms whereby certain of the warp threads are crossed relatively to others to produce the cross or marquisette weave.

15 The object of the present invention is to provide a cross weaving loom of simple construction and wherein many of the complicated features heretofore present in looms of this character are eliminated; and the loom 20 rendered efficient and practical in operation. The invention and its various improved and novel features will best be made clear from the following description and accompanying drawings of one good form of means for 25 carrying it into practical effect.

In the drawings:—

Fig. 1 is a sectional side elevation longitudinally through a cross weaving loom containing the present invention, some of the 30 parts being omitted for clearness of illustration;

Fig. 2 is a perspective view on an enlarged scale, showing more particularly the cross weaving mechanism and the means for operating the heddles in the formation of the cross-weave effect, the doup and other heddle details being represented diagrammatically only;

Fig. 3 is an enlarged detached detail showing the rockers, preferably located at the top of the loom for operating the lifter and jumper heddles;

Fig. 4 is a side view of the parts shown by Fig. 3, some of the elements being broken 45 away to illustrate the interior constructions;

Fig. 5 is an enlarged perspective detached view of one form of doup and lifter heddles which may be employed in connection with 50 the present invention; and

Fig. 6 is an enlarged detail showing more particularly the construction and connection of the lifter and doup heddles.

The loom frame 1 supports the usual crank 55 shaft 2 which is connected to the lay 3 for

imparting to the lay its well-known beatup movements. Mounted upon the loom frame in suitable bearings below the crank shaft 2 is the under or cam shaft 4, Fig. 1, which is driven from the crank shaft in the ratio of one to two, that is, the gearing connection between the crank shaft and under or cam shaft 4 effects one rotation of the under or cam shaft upon two complete rotations of the crank shaft; and inasmuch as the present invention contemplates that certain of the heddles shall be given a two-to-one motion with relation to other of the heddles, as will presently appear, advantage is taken of the relation between the crank and under 60 or cam shaft to effect such motion of the heddles. 65

In the construction illustrated in Figs. 1 and 2, two doup heddles are shown, each associated with two lifter heddles, but it will 70 be understood that one doup heddle and two lifter heddles constitutes a unit of the cross weaving mechanism.

The construction and relation of the doup and lifter heddles for controlling the doup 80 warp thread of a unit is shown in Figs. 5 and 6, but this feature constitutes no essential part of the present invention, and is illustrated for the purpose of making clear that the doup thread is operated on each shed 85 formation to place the doup thread in the same plane of the shed. The construction shown by Figs. 5 and 6 constitutes a convenient and effective arrangement of the doup and lifter heddles, but other forms of 90 such doup and lifter heddles may be employed within the true scope of the present invention.

The doup heddle 5, Figs. 5 and 6, is constituted with two leg portions 6, one of 95 which passes through an opening 7 in one lifter heddle 8, while the other passes through a similar opening 9 in the other lifter heddle 10. The doup heddle 5 has the eye 11 through which the doup thread *a* 100 passes.

The legs 6 of the doup heddle 5 extend downwardly and are connected at their lower ends by the bars 12, which are normally held downwardly by the yokes 13, to the lower 105 end of which a spring 14 is secured, the construction being such that the doup heddle 5 is normally and yieldingly held depressed.

The lifter heddles 8 and 10 are connected to their respective heddle frames 15 by the 110

hooked upper and lower portions 16, the construction being such that when either of the heddle frames 15 and its connected lifting heddle 8 or 10 is moved upwardly, in 5 the present instance, the doup heddle 5, one leg of which passes through the opening 7 in the lifter heddles, will be raised and 10 force the doup thread *a* which passes through the eye 11 of the doup heddle, will likewise be raised and consequently always be placed in the same line or plane of the shed in successive shed formations. Suitable springs 17, Fig. 2, are connected to the lower portion of each lifting heddle frame to normally depress the connected heddle frame. 15

Each doup thread *a* has associated with it a jumper thread *b* which passes between the two lifter heddles 8 and 10, and through the eye 18 of a jumper heddle 19 which is mounted in the jumper heddle frame 20, Fig. 2. The jumper heddle frame 20 and the jumper heddles 19 carried by the frame are preferably mounted rearwardly of the lifting heddle frames, as indicated in Fig. 2. 20

The loom frame supports one or more warp beams 21, Fig. 2, on which are wound the doup and jumper warp threads. The doup and jumper warp threads pass from the source of supply over the whip-roll 22, Fig. 2, and over and under the lease rods 23, from which they extend forwardly toward the front of the loom. All of the doup threads *a*, Figs. 1 and 2, pass under an evener bar 24 which is guided for movement by guides 25 secured to the loom frame, and is normally under the control of a spring 26, one preferably being connected to the evener bar near each end thereof. The evener bar 24, therefore, is above the doup 25 threads and normally rests upon the doup threads under the yielding influence of the spring 26 to thereby even up the doup thread during the cross weaving operation. From the evener bar 24, each doup thread *a* passes through an eye 11 of one of the doup heddles, as clearly indicated in Fig. 5, and then the doup thread leads through the usual reed carried by the lay. The associated jumper warp thread *b* passes from 30 the warp beam over and under the lease rods 23 and through the eye 18 of the jumper heddle 19 and then between the two lifter heddles 8 and 10, whence it extends forwardly through the same dent of the reed 35 with its associated doup thread.

From the construction thus far described it will be clear that when the shed is closed, that is, when the doup and jumper warp threads are in substantially the same plane, 40 if one of the lifter heddles be raised, and the jumper heddle be lowered, the doup thread *a* will be passed at one side of the jumper thread in the shed formation and that all the doup threads will be in one plane of the shed, 45 while all the jumper threads will be in the

other plane of the shed. Similarly, when the other lifter heddle is raised from the closed shed position, it will raise the doup heddle and with it the doup thread, to the opposite side of the jumper thread and the 50 jumper threads may be then lowered to form the lower plane of the shed. Thus in each successive shed formation, the lifter heddles alternately raise the doup heddle and the associated doup thread first at one and then 55 at the opposite side of the jumper thread and place it in the same plane of the shed on each shed formation; while the jumper thread is raised to the plane of the closed shed and then depressed to complete the 60 shed, on each shed formation. In other words, every time the shed is formed, the doup threads are moved into the same shed plane on each formation, and the jumper thread is moved into the other shed plane, 65 the doup thread being passed alternately back and forth across the jumper thread.

To impart the alternate movements to the lifting heddles and the two-to-one movement of the jumper heddle, the present invention provides a connection between the under or cam shaft for operating the lifting heddles and a connection to the crank shaft for operating the jumper heddle, one form of such connection being shown in the 95 accompanying drawings, especial reference being made to Figs. 2, 3 and 4.

The loom arch 27, Figs. 1 and 2, has mounted thereon two rockers, one of which receives motion from the under or cam shaft, 100 and is connected to the lifting heddles and the other of which is operated from the crank shaft and is connected to the jumper heddle, with the result that the jumper heddle is given an up-and-down movement of 105 the lifting heddles.

As shown in the present form of the invention, the loom arch 27 has extending upwardly therefrom the brackets 28 and 29, which carry the dead or stud shaft 30. 110 Mounted for rocking movement on the dead shaft 30 is the rocker 31 which may be conveniently formed as a cylinder, Figs. 3 and 4. Secured to the rocker 31 is an arm 32 pivotally connected at 33 to the upper end 115 portion of a rod 34. In the present instance the connection between the arm 32 and the rod 34 is formed by the yokes 35 and 36, flexibly connected by the pin 37 in order to prevent binding of parts due to 120 the difference in the directional movements that may occur between the rod 34 and the arm 32 during the loom operation. The rod 34 is connected in a similar manner by the yokes 38 and 39 to a crank arm 40 secured 125 to the lower or cam shaft 4, Fig. 2. The rocker 31 is connected to the lifting heddle frame, when one is used, or to the two lifting heddle frames 15 in the present form 130 of the invention, by means of the straps or

flexible elements 41 which may be suitably guided above their points of attachment to the lifting heddle frames by the guides 42, supported by the loom arch. The connecting elements between the rocker 31 and the lifter heddle frames may be variously formed, but the character of the connection herein shown is found to be advantageous in practical operation, the construction being such that upon rocking movement of the rocker 31 one of the lifting heddles 15 will be raised and the other will be lowered.

The jumper heddle 20, in the present invention, is to have a two-to-one motion as compared with the associated lifting heddle, and is shown as connected through a rocker to the crank or main shaft 2 of the loom.

Loosely mounted on the stud shaft 30 is the second rocker 43 to which is secured an arm 44 adjustably connected at its outer end at 45 with the operating rod 46. The construction between the operating rod 46 and the arm 44 is preferably formed by the yokes 47, and 48, pivotally connected at 49 in a manner similar to the yokes 35 and 36, hereinbefore described. The rocker 43 has adjustably connected thereto, the segment 50 to which is secured the jumper heddle operating connection 51.

The rod 46 at its lower end is connected to the crank arm 52 secured to the main or crank shaft by the yokes 53 and 54 pivotally connected at 55, the construction being such that upon each rotation of the crank shaft the jumper heddle will be raised and lowered; and since the lower or cam shaft makes one revolution to each two revolutions of the crank shaft, it follows that upon each rise and fall of the jumper heddle one of the lifter heddles will be raised. From the construction described it will be apparent that on each shed formation, the jumper thread will always appear in the same shed plane and that the doup thread will always appear in the opposite shed plane.

It sometimes is desirable that the fabric being woven with the cross weave or marquisette effect have a plain or other form of woven selvage. To this end the present invention provides selvage heddles and selvage thread spools, and where the selvage threads are to be alternately raised and lowered, as shown in the present instance, the selvage heddles, two of which are shown, are connected for alternate movement to the rocker 31 hereinbefore described.

The selvage threads are carried by spools or beams 56 supported upon arms 57 extending from the loom arch, and a friction let-off formed by a band 58 passing around a rim of the selvage spool and connected to a spring 59 maintains the selvage threads leading from the selvage spools under proper tension. The selvage threads pass around the whip-roll 22 at each side of the

loom, and thence pass to and through the respective heddles carried by the heddle frames 60, one of which is shown up and the other down, in Fig. 2.

What is claimed is:—

70

1. In a cross-weaving loom, the combination of the crank shaft, an under or cam shaft making a single revolution to each two revolutions of the crank shaft, a doup heddle for controlling a doup thread, two lifter 75 heddles for alternately operating the doup heddle for placing the doup thread in the same plane of the shed on each shed formation, a jumper heddle for controlling a jumper thread and placing it in the same 80 shed plane on successive shed formations, connections between the lifter heddles and under or cam shaft for operating the lifter heddles, and connections between the crank shaft and jumper heddle for operating the 85 jumper heddle two-to-one relative to the lifter heddles.

2. In a cross-weaving loom, the combination of the crank shaft, an under or cam shaft making a single revolution to each two 90 revolutions of the crank shaft, a doup heddle for controlling a doup thread, two lifter heddles for alternately operating the doup heddle for placing the doup thread in the same plane of the shed on each shed formation, a jumper heddle for controlling a jumper thread and placing it in the same shed plane on successive shed formations, connections between the lifter heddles and under or cam 95 shaft for operating the lifter heddles, connections for operating the jumper heddle two-to-one relative to the lifter heddles, and a spring controlled evener bar resting upon the doup threads.

3. In a cross-weaving loom, the combination of the crank shaft, an under shaft, a doup heddle for controlling a doup thread, two lifter heddles for alternately operating the doup heddle, a jumper heddle for controlling a jumper thread, connections between the lifter heddles and under shaft including a crank for operating the lifter heddles, and connections between the jumper heddles and crank shaft for operating the 100 jumper heddles two-to-one relative to the 105 doup heddles.

4. In a cross-weaving loom, the combination of a doup heddle for controlling a doup thread, two lifter heddles for alternately operating the doup heddle to place the doup 110 thread in the same plane of the shed on each shed formation, a jumper heddle for controlling a jumper thread and moving it to the same shed plane upon successive shed formations, means connected to the under or cam shaft for operating the lifter heddles, and means connected to the crank shaft for operating the jumper heddle two-to-one relative to the doup heddles.

5. In a cross-weaving loom, the combi- 115

120

125

130

nation of a doup heddle for controlling a doup thread, two lifter heddles for alternately operating the doup heddle to place the doup thread in the same shed plane on

5 successive shed formations, a jumper heddle for controlling a jumper thread and placing it in the same shed plane on successive shed formations, selvage heddles for controlling selvage threads connected with 10 the under or crank shaft of the loom and the lifter heddles and also with the selvage heddles for operating them, and connections with the crank shaft and jumper heddle for operating the jumper heddle two- 15 to-one relative to the lifter and selvage heddles.

6. In a cross-weaving loom, the combination of a doup heddle for controlling a doup thread, two lifting heddles for alternately 20 operating the doup heddle to place the doup thread in the same plane of the shed on each shed formation, a jumper heddle for controlling the jumper thread and moving it into the same shed plane upon successive 25 shed formations, an evener bar above the doup thread, and yielding means acting upon the evener bar for evening up the doup threads.

7. In a cross-weaving loom, the combination of a doup heddle for controlling a doup thread, two lifting heddles for alternately operating the doup heddle to place the doup thread in the same plane of the shed on each shed formation, a jumper heddle for controlling the jumper thread and moving it into the same shed plane upon successive shed formations, an evener bar above the doup thread, and a spring normally acting to depress the evener bar upon 40 the doup threads.

8. In a cross-weaving loom, the combination of a doup heddle and two controlling lifter heddles for alternately lifting the doup heddle and the doup thread to the upper plane of the shed on successive shed formations, a jumper heddle for moving the jumper thread to the lower plane of the shed on successive shed formations, an evener bar located above the doup threads back 50 of the heddles and a spring for causing the evener bar to yieldingly bear upon the doup threads.

9. A cross-weaving loom having a doup thread evening bar which rests upon the 55 doup threads and is movable in one direc-

tion by the doup threads during the formation of a shed, and a spring acting yieldingly upon the evener bar in the opposite direction.

10. In a cross-weaving loom having a warp beam supply for doup and jumper warp threads, a separate supply for selvage threads, a spring operated evener bar acting upon the doup warp threads, heddles for separately controlling the doup, jumper, and selvage warp threads, connections with the under or cam shaft for operating the doup and selvage heddles, and connections with the crank shaft for operating the jumper heddle two-to-one relative to the doup and selvage heddles.

11. In a cross-weaving loom, the combination of a doup heddle, two lifting heddles for alternately lifting the doup heddle to the upper plane of the shed on each shed formation, a jumper heddle, a crank connected to the under or cam shaft for operating the lifter heddles to place the doup thread in the upper plane of the shed on each shed formation, and a crank connected to the crank shaft for operating the jumper heddle.

12. In a cross-weaving loom having a warp beam supply for doup and jumper warp threads, a separate supply for selvage warp threads, a whip roll about which the doup, jumper, and selvage warp threads pass, a spring controlled evener bar for evening the doup threads, and heddles for controlling the doup, jumper, and selvage threads in the formation of the successive sheds.

13. In a cross-weaving loom, the combination of a doup heddle, lifter heddles for controlling the doup heddle to place the doup thread in the same shed plane on successive shed formations, a jumper heddle for placing a jumper thread in the same shed plane on successive shed formations, a rocker, connections between the rocker and lifter heddles operated from the under or cam shaft for operating the lifter heddles, and a second rocker connected to the jumper heddle and crank shaft of the loom for operating the jumper heddle two to one relative to the lifter heddle.

In testimony whereof, I have signed my name to this specification.

GEORGE E. SPOFFORD.
